HOLDER FOR RAZOR BLADES

Franklin S. Flagg, Hartford, Conn.

Application November 4, 1935, Serial No. 48,122

2 Claims. (Cl. 30—101)

This invention relates to an improved holder for use in temporarily holding safety razor blades for the purpose of stropping or honing the same.

There are a number of razor blade holders now 5 on the market but it is well known that, in the use of such holders, there is present the danger of the user cutting his fingers while inserting the blade in the holder and particularly while clamping the blade therein.

10 An object of my invention, therefore, is to provide a holder of this type in which a blade can be easily inserted and which can be operated, to clamp the blade therein, in a manner whereby the user's hand is safely removed from the cutting 15 edge of the blade.

A further object of this invention is to provide such a holder in a form which is adapted to receive blades of various types, such as either the single or double edge blades, in a manner whereby 20 the said blades may be easily inserted into or quickly removed from the holder and also securely held thereby during the stropping or honing operation.

My invention is clearly illustrated in the accompanying drawing in which:

Figure 1 is a perspective view of my improved holder showing a blade of the double edge type inserted therein.

Figure 2 is a side view thereof, in central vertical section, showing a blade in dotted lines as clamped therein.

Figure 3 is an end view of the same, on line 3—3 of Figure 2, with a blade shown in full lines therein.

35 Figure 4 is a similar view showing the holder in closed position with the blade removed therefrom.

Figure 5 is a view in longitudinal section on line 5—5 of Figure 3 illustrating the holder in its open 40 position and ready to receive a blade.

Figure 6 is a similar view showing the holder in closed position and with a blade clamped therein.

Figure 7 is a view in longitudinal section on 45 line 7—7 of Figure 3.

Figure 8 is a view illustrating the operation of opening the holder to remove the blade therefrom.

Figure 9 is a similar view illustrating the 50 operation of closing the holder to clamp the blade therein.

In the form shown in the drawing, my improved holder comprises a blade gripping member 5 which is constructed of a single piece of sheet material 55 and formed to provide a tubular body portion 6

and blade gripping jaws 7 extending therefrom. The body portion 6 extends from one side of the jaws to form a handle portion 8.

A clamping member 9 is provided to slidably fit over the body portion 6. The said clamping member has clamping jaws 10 extending over a portion of the gripping jaws 7 which are adapted to squeeze, or clamp, the said gripping jaws together. This clamping member is of substantially the same form as the gripping member 5 10 with the exception that it has a handle portion 11 which is shorter than the handle portions 8 of the gripping member and is knurled near its end to provide a finger grip remote from the razor blade.

The gripping member 5 is preferably constructed of a sheet material which is thinner than that of the clamping member 9 so that, when the said clamping member is moved into clamping position upon the gripping member, the jaws 10 20 thereof will force the gripping jaws 7 together causing them to flex and engage the blade 12 at two points in the manner clearly shown in Figure 3 of the drawing.

The operation of this improved holder is as 25 follows:

When it is desired to remove a blade therefrom, the holder is gripped by the handle portion 11, of the clamping member 9, as clearly 30 illustrated in Figure 8 of the drawing. The end of the handle portion 8 is placed against a suitable surface and the clamping member 9 is slid downwardly over the gripping member until the ends of both handle portions are brought together upon the said surface. At this time the clamping jaws 10 are in the position shown in Figure 5 of the drawing, in which position they have released the gripping jaws 7 so that the blade can be easily removed therefrom.

When it is desired to place a blade in the holder, the said blade is inserted to the position shown in Figure 2 of the drawing, the holder is placed against the surface, as clearly shown in Figure 9, and the clamping member is slid back 35 into the clamping position, as shown in Figure 6, thus forcing the gripping jaws together and securely holding the blade in the holder.

It will be noted that the forward ends of the clamping jaws 10 are slightly flared, as illustrated at 13, in order that they will easily slide over the gripping jaws 7 when moved to the clamping position. These flared portions, however, do not extend above the edges 14 of the clamping jaws 10 so as to avoid any projection 55

that would come into contact with the surface of the strop or hone which is being used.

It will also be noted that when the clamping member is moved to the position shown in Figures 5 and 8, the ends of the clamping jaws 13 still remain in engagement with the ends of the gripping jaws 7 to prevent rotation of the clamping member 9 upon the gripping member 6 and thus retain the clamping jaws in operating relation with respect to the gripping jaws.

It will be readily understood, from the above description, that I have provided a holder which is extremely simple in construction and efficient in its operation, and also, a holder which is easily operated with the use of one hand, for inserting or removing a blade therefrom, in a manner which is extremely simple as well as safe against injury to the user.

I claim:

20 1. A razor blade holder comprising a gripping member having a tubular body portion, a handle, gripping jaws extending from said body

portion, parallel gripping surfaces on said gripping jaws, a clamping member slidable upon said gripping member, clamping jaws extending from said clamping member to a point intermediate said gripping surfaces and adapted to 5 clamp said gripping jaws together for gripping a blade therebetween, and a handle extending from said clamping member.

2. A razor blade holder comprising a gripping member, a pair of gripping jaws extending from 10 said gripping member to receive a razor blade therebetween, said gripping jaws having a plurality of parallel linear gripping surfaces to engage with said blade, a clamping member 15 slidable upon said gripping member, clamping jaws on said clamping member extending therefrom over a portion of said gripping jaws to a distance intermediate said linear gripping surfaces to force the same into engagement 20 with said blade.

FRANKLIN S. FLAGG.
